EARRING

Elena Mariani, East Orange, N.J., assignor to Coro, Inc.,
Providence, R.I., a corporation of New York

Filed May 17, 1967, Ser. No. 7,164

Term of patent 14 years

(Cl. D45—9)

FIG. 1

FIG. 2

FIG. 3

FIG. 4

FIG. 1 is a front elevational view of an earring showing my new design;

FIG. 2 is a rear elevational view thereof;

FIG. 3 is an end elevational view thereof; and

FIG. 4 is a top plan view thereof.

The characteristic feature of my design resides in an earring having the pendant portion formed from a continuous, spirally wound wire suspended only at its opposite ends, although giving the appearance of a series of independent hoops.

This is a continuation-in-part of design application Ser. No. 5,788, filed Feb. 13, 1967, and now abandoned.

I claim:

The ornamental design for an earring, substantially as shown and described.
